UNITED STATES PATENT OFFICE.

GEORGE A. MEYER, OF BROOKLYN, NEW YORK.

ILLUMINATED SIGN-BOX.

SPECIFICATION forming part of Letters Patent No. 393,779, dated December 4, 1888.

Application filed April 19, 1888. Serial No. 271,244. (No model.)

To all whom it may concern:

Be it known that I, GEORGE A. MEYER, a citizen of the United States, and a resident of Brooklyn, in the county of Kings and State 5 of New York, have invented certain new and useful Improvements in Illuminated Sign-Boxes, of which the following is a specification.

My invention relates to the construction of 10 the box or body portion of illuminated signs or lanterns; and it consists of certain novel features, hereinafter described, for producing an effective ventilation of said box, and of an ornamental border thereon; also for protecting 15 the light medium of the box against rain-water or direct draft, and for obtaining a superior reflection of light from the box, as into a window.

In the accompanying drawings, Figure 1 20 represents a partial rear view and partial vertical longitudinal section of a sign-box embodying my invention. Fig. 2 represents a partial front view and partial vertical longitudinal section taken through the border 25 thereof. Fig. 3 represents a partial top view and partial horizontal section thereof. Fig. 4 represents a vertical cross-section thereof. Figs. 5 and 6 represent detail views of parts.

Similar letters of reference indicate corresponding parts.

The letter A indicates the bottom, B the top or roof, C the ends, D the front side, and E the rear side, of the box, the whole formed 35 of sheet metal or other suitable material and provided with hooks or other means for suspending it in the desired place.

In the roof B are ventilating-holes *a*, the edges of which may be provided with flanges *b*, to connect with suitable air-outlet pipes, 40 and beneath said holes, in the upper part of the box, is a pan, F, for receiving any rain-water, dust, or other matter that may enter through the ventilating-holes. Said pan F is suspended from the roof by means of brackets 45 *c*, to permit its removal from the box, and from the pan extends a pipe, G, downwardly through the bottom A, for carrying off the water that may accumulate in the pan. The pipe G thus acts as a drain, while it also permits an upward passage of air from the outside of the box to the space above the pan, thereby cre-

ating a draft through the roof-holes *a*, for better ventilating the box. On the top end of the pipe G is a telescopic section, G', held in place by a spring-catch, *d*, for adapting said 55 pipe to be disconnected from the pan. Air is admitted to the interior of the box through ventilating-holes in a border, H, to be presently described, or, if said border be omitted, through corresponding holes formed on or 60 near the bottom A, it thence passing upward around the pan F to the roof-holes.

The border H is on the edges of the front D of the box, it being for the purpose of ornament, and is made in sections, (marked *e* and *e'*), 65 each of which is open on the rear side and perforated on the front side, the whole being hollow, as more clearly shown in Figs. 5 and 6. Those portions of the border-sections forming the bottom and ends of the border are each 70 fitted with a transparent or semi-transparent plate, *f* or *f'*, which may be composed of glass or mica, while those portions of the sections forming the top of the border are left entirely 75 open, thus freely communicating with the interior of the box, so that the air may escape from the top portion of the box through the perforated front side of said top border-sections. The border-sections *e* *e'* alternate with each other, and the plates *f* of the sections *e* 80 are fitted into the front portions thereof, (see Fig. 5,) in distinction from the plates *f'* of the sections *e'*, which are fitted into the rear portions thereof, (see Fig. 6,) so that the sections *e* communicate freely with the interior of the 85 box, while the sections *e'* form a continuous air-passage, whereby a very effective ventilation of the border is produced. At a point in rear of said top of the border, within the box, is a reflector, I, Fig. 4, the essential purpose 90 of which is to hide the interior parts of the box from view through the holes of the border, and on the rear lower part of said top of the border is an upturned flange, *g*, Fig. 4, which acts as a water-shed to catch and throw 95 off any rain-water that may enter through said holes.

The rear side, E, of the box is open, it being usually provided with hinged doors *E'*, with glass plates for the free passage of light rearwardly from the box, while the front side, D, of the box is provided with an illuminated

sign, D', of any usual or suitable construction, and which may have a reflector on the rear side. Said rear open side, E, of the box is inclined from top to bottom toward the front of the box, as shown in Fig. 4, and in the upper part of the box is a reflector, J, preferably of curved cross-section and electro-nickel-plated, which serves to throw the light from the box downwardly through said inclined side, so that if the box is placed in front of a show-window, at the top thereof, the window may be very effectively illuminated from the box. Said reflector J is suspended from the top of the box by pivoted supports i, which are on or near one edge thereof parallel to the sides of the box, the other edge being sustained by a bracket or spring-catch, l, for adapting the reflector to be adjusted to any angle in relation to the rear side of the box with a corresponding adjustment in the direction of the reflected rays of light. The illuminating medium of the box is in this example a gas burner or burners, K, to which access is had through gravitating doors 25 in Fig. 1, in the bottom of the box, and which burners may be provided with reflectors K', of frusto-conical shape, to co-operate with the reflector J, above mentioned. For the purpose of supporting the border 30 H the front side of the box may have a flange, O, Fig. 1, provided with openings corresponding to the several border-sections, upon which the sections may be fastened. What I claim as new, and desire to secure 35 by Letters Patent, is—

1. A sign-box having ventilating-holes in the roof thereof, in combination with a pan beneath said holes in the upper part of the box, and a combined drain and ventilating 40 pipe extending from said pan through the bottom of the box, substantially as and for the purpose described.
2. A sign-box having ventilating-holes in the roof, and also in or near the bottom thereof, in combination with a pan beneath said holes in the upper part of the box, and a combined drain and ventilating pipe extending from said pan through the bottom of the box, substantially as and for the purpose described.
3. In a sign-box, the combination of a hol-

low border, open on the rear side and perforated on the front side, and transparent or semi-transparent plates fitted into the rear portion of said border to form a continuous air-passage, substantially as and for the purpose described. 55

4. In a sign-box, the combination of a hollow border, open on the rear side and perforated on the front side, and transparent or semi-transparent plates fitted into the rear portion of the bottom and ends of said border, leaving the top thereof free to communicate with the interior of the box, substantially as and for the purpose described. 60

5. In a sign-box, the combination of a hollow border made in sections, each open on the rear side and perforated on the front side, and transparent or semi-transparent plates fitted into the front and rear portions, respectively, of alternate sections of said border, to permit 70 alternate sections thereof to communicate with the interior of the box, substantially as and for the purpose described. 65

6. In a sign-box, the combination of a hollow border, open on the rear side and perforated on the front side, and a reflector within the box in rear of said border, substantially as and for the purpose described. 75

7. In a sign-box, the combination of a hollow border, open on the rear side and perforated on the front side, and a flange on the rear lower part of said border acting as a water-shed, substantially as and for the purpose described. 80

8. A sign-box having a rear open side inclined from top to bottom toward the front of the box, in combination with a reflector in the upper part of the box, substantially as and for the purpose described. 85

9. A sign-box having a rear open side inclined from top to bottom toward the front of the box, in combination with a reflector in the upper part of the box, pivoted on one edge for its adjustment in relation to said inclined side of the box, substantially as and for the purpose described. 95
